UNITED STATES PATENT OFFICE.

ROBERT MIEHLE, OF CHICAGO, ILLINOIS, ASSIGNOR OF ONE-HALF TO MIEHLE PRINTING PRESS & MANUFACTURING COMPANY, OF CHICAGO, ILLINOIS, A CORPORATION OF ILLINOIS.

SHEET-DELIVERY MECHANISM FOR PRINTING-PRESSES AND OTHER MACHINES.

991,002.

Specification of Letters Patent.

Patented May 2, 1911.

Application filed November 20, 1903. Serial No. 181,904.

To all whom it may concern:

Be it known that I, ROBERT MIEHLE, a citizen of the United States, residing at Chicago, in the county of Cook and State of Illinois, have invented certain new and useful Improvements in Sheet-Delivery Mechanisms for Printing-Presses and other Machines, of which the following is a full, clear, and exact specification.

10 This invention relates to that character of mechanisms for delivering sheets upon a piling-table, or other support, as they come from a printing press, or other machine, by which the sheet is printed upon or otherwise treated, in which the sheet is inverted or turned over upon the table; and the invention has for its object to provide an improved and compact form of a delivery mechanism of the described character, especially adapted to run or operate at a very high rate of speed, as for example where applied to a single impression sheet rotary press.

15 With these ends in view my invention consists in certain features of novelty in the construction, combination and arrangement of parts by which the said objects and certain other objects hereinafter appearing are attained, all as fully described with reference to the accompanying drawings and more particularly pointed out in the claims.

20 In the said drawings—Figure 1 is a side elevation of a rotary cylinder printing press to which the invention is applied. Fig. 2 is an enlarged detail plan view of the sheet delivery mechanism proper with some of the coöperating parts of the printing press. Fig. 3 is an enlarged detail plan view of one of the links of a chain employed in the invention, showing the manner of journaling a roller therein. Fig. 4 is a side elevation thereof, partly broken away. Fig. 5 is a vertical longitudinal section thereof. Fig. 6 is a similar section with the parts in a different position and taken in a different plane from Fig. 5, and Fig. 7 is the same section showing the parts in the act of dropping the sheet upon the table.

25 Fig. 1 is a feed board or table, 2 the cylinder driven by gear 2^a from usual pinion 2^b on the drive shaft and 5 the inking apparatus, all of the ordinary or any suitable construction usual on rotary cylinder printing presses. The main shaft 6 of cylinder 2

drives a gear 7, which meshes with a gear 8, 55 and this in turn revolves suitable grippers 9 which meet the grippers 3 and receive the sheet therefrom and deliver it to the side of the revolving grippers 10 mounted upon and revolving around a shaft 11, which latter 60 also carries a gear-wheel 12 which meshes with and derives motion from the gear 8, and on the shaft 11 are also mounted a number of tape drums or wheels 13 over which run bands or tapes 14, the tapes 14 being 65 also supported by and running over one or more rollers 15.

Mounted over the tape wheels or drums 13 is a pressure roller 16, which is adapted at certain times during the operation to press 70 upon the tapes 14 so as to cause the sheet, which is shown at 17, to travel upwardly onto the tapes 14 when delivered by the grippers 10 with its upper edge between said tapes and the roller 16, the tapes and said 75 roller 16 thus serving to advance the sheet toward the right under a set of upper fingers 18, and over a set of lower fingers 19, which serve to hold the sheet flat and in position. The grippers 3 are actuated by the 80 mechanism usually provided for such purpose on machines of this character, and the grippers 9, 10 may be actuated by the same character of mechanism, or by any other suitable mechanism, but the mechanism 85 shown for actuating these grippers 9, 10 consists of the devices which are shown in connection with the upper set of grippers 10, and a description of which will suffice also for the grippers 9. This mechanism 90 consists of a rocker shaft 20, to which the grippers 9, or 10 are secured, and to which is also secured a rocker arm or lever 21, to each end of which is pivoted the usual spring-actuating device 22, which serves to close 95 the grippers when not otherwise restrained, and in the other end of which is journaled a roller 23, which rests on a cam 24 having cutaway places or depressions 25 of such form and arrangement as to allow the grippers to close and remain closed while they are taking the sheet from the grippers 9 and delivering it to the tapes 14 and roller, the cam 24 of course being fixed with relation to the shaft 11, around which the grippers 10 revolve and the same gripper actuating mechanism being used for the grippers 9, the cam 24, which corresponds thereto, but

which is not necessary to illustrate in connection therewith, is similarly fixed with relation to the shaft 26 around which the grippers 9 revolve and on which the gear 8 5 is mounted.

Secured to or formed on the main frame 27 of the printing press is an extension frame comprising two horizontal portions, 28, 29, arranged substantially parallel, as 10 shown in Fig. 2, and two upright portions or standards 30, 31, which together with standards 27^a of the main frame serve to sustain the horizontal portions 28, 29 and to 15 also support a piling table 32 which receives the sheets from the delivery mechanism. Extending across the inner ends of horizontal frame members 28, 29, is a shaft 33, upon which, adjacent to frame members 28, 29, are loosely mounted two sprocket or chain 20 wheels 34, 35, while at the opposite ends of the members 28, 29, are journaled two similar sprocket or chain wheels 36, 37, but these latter are mounted on short or stud shafts 38, 39, respectively, which do not extend 25 across the space between the members 28, 29. Arranged on and traveling over the sprockets 34, 36, is a chain belt 40, and arranged on and traveling over the sprockets 35, 37 is a similar chain belt 41. 42 are belt 30 tightening devices of a well known form and mode of operation for taking up the slack in these belts 40, 41, when necessary, and the inner sides of the frame members 28, 29, are provided with inwardly projecting flanges 35 43, 43^a, and these flanges 43, 43^a, serve for supporting the upper and lower folds respectively of the belts 40, 41. The two chain belts 40, 41, are for the purpose of carrying a cross bar or sheet smoothing member, 40 which is shown in the form of a roller 44, and extends outward the space between the two belts 40, 41, and travels with such belts in such a manner as to engage the under side of the sheet 17 and turn it upside down, or 45 reverse it, while the forward edge of the sheet is being pulled downwardly over the roller 44 by suitable grippers 45, in the manner better illustrated in Fig. 6.

In order that the action of the bar 44 50 against the under side of the sheet may be in conformity with the direction of movement of the sheet, and therefore serve to assist the sheet in its travel rather than retard it by frictional contact, such bar 44 is made as 55 aforesaid in the form of a roller which is rotatable in the direction of travel of the sheet by contact with a bearer or horizontal bar 46, which is arranged at one end of the roller 44 along the inner side of belt 40 and 60 provided with a leather surface, or other suitable bearing surface, 47, for engagement with the under side of roller 44 as the latter travels with the chain, thereby causing the roller to revolve in harmony with the 65 movement of the sheet 17 as the sheet and

the roller proceed together, and consequently serve to invert the sheet and turn it end over end as its forward edge is held by the grippers 45 and the roller 44 proceeds the length of the belts 40, 41, while engaging the under 70 surface of the sheet. The grippers 45 are of course provided with some suitable mechanism for causing them to engage the sheet at the proper time as it emerges from the ends of the supporting fingers 19, and to 75 drive or rotate such grippers at such a rate of speed that the roller 44 may travel from its position shown in Fig. 5, or any other suitable position, to the left of the point where the grippers 45 engage the sheet, to 80 the point at the opposite ends of the belts 40, 41, as shown in Fig. 7, where the sheet is completely inverted and ready to fall upon the table 32, mechanism of suitable form being also provided for causing the pressure 85 roller 16, to release its grip upon the sheet when the grippers 45 take possession of it, because when the smoothing bar or roller 44 engages under the sheet and pulls it forward the rear end of the sheet travels at a greater 90 rate of speed than the tapes 14. The mechanism for accomplishing these movements and results will now be explained.

Suffice it to say that the grippers 45 are opened and closed by any well known mechanism usually employed for this purpose, such, for example, as that already described for operating the grippers 9, 10, and which comprises a spring actuated device 48 engaging one end of a lever or rocker shaft 95 49, which is secured to the rocker shaft 50, which carries and operates the grippers 45, the shaft 50 being journaled in suitable brackets 51 secured to the shaft 33 and revolving therewith. On the other end of 100 lever 49 is mounted an anti-friction roller 52 which rides upon a cam 53 so shaped as to compress the spring 48 and throw the grippers 45 open when they arrive at their lower position, as indicated in Fig. 7, or at 105 the point where the sheet has been completely inverted by the action of the roller 44 and is ready to drop upon table 32, and to hold them open until they arrive at the position indicated in Fig. 5, where the forward end 110 of the sheet 17 is projected beyond the fingers 19 and is ready to be received by such grippers 45. The cam 53 is fixed against rotation with the grippers by any 115 suitable means, such as a bracket 54, secured by a bolt or other means 55 to the inner side of a boss 56 or on the inner side of frame member 29. Coöperating with each one of the grippers 45 is what might be 120 termed the stationary or fixed jaw 57 of such gripper, serving as a support for the sheet while it is being pinched by the movable jaw 45 of the grippers, and these jaws 57 are formed on curved arms 58, whose upper edges are so rounded as to form an 125 130

easy surface for the sheet to rest on while it is being pulled downwardly in the manner shown in Fig. 6, by the grippers 45. These arms 58 are curved around one side of and rigidly secured to the shaft 33 by means of screws or bolts 59, so that they may be removed, together with the arms 51 and grippers 45, if it should be desired to do so, and in order that they may be more rigid, and thus removed as a whole, their ends opposite the jaws 57 are rigidly connected together by a rod 60 and pin 61, it being understood that the shaft 33, arms 51, 58 and grippers 45 revolve together, but these parts are capable of revolving independently of the sprocket wheels 34, 35, which are given a more rapid speed of rotation than the grippers 45 in order to enable the roller 44 to reach the opposite end of the belts 40, 41, as shown in Fig. 7, by the time the grippers 45 reach a position at the under side of the sprockets, as shown in said figure, where the edge of the sheet comes contiguous to the usual stop bars or gages 62 arranged at the end of table 32. The sprockets 34, 35, are provided with gear wheels 63, 64, rigidly secured to or formed thereon, but loose on the shaft 33, and these gear wheels 63, 64 engage with pinions 65, 66, respectively, and are driven thereby, the pinions 65, 66, being mounted and secured upon and driven by a shaft 76 which derives motion from a pinion 68 on the outer end of the shaft 67 meshing with a large gear 12, which is fixed to shaft 11, the gear 12 deriving motion, as before explained, from the gear 8, or other suitable connection with the cylinder of the press. By this train of gearing the sprockets 34, 35 are driven at a higher rate of speed than shaft 38, or at least at a higher rate of speed than that at which the shaft and grippers 45 revolve throughout a portion of the revolution, the speed of revolution of such shaft and grippers being differential, or slower at one time than at another as a result of the employment of any suitable differential speed mechanism, such as elliptical gears 72, 73, connected in any suitable way with the shaft 33 and with the operating mechanism of the press through the intermediary of suitable instrumentalities. These gears 72, 73 are shown as intermeshing with each other and gear 72 is mounted upon and rigidly secured to shaft 33 and gear 73 is loosely mounted upon a short or stud shaft 74, upon the latter of which is journaled a large gear wheel 75, which is secured to and revolves the elliptical gear 73, both gears 73, 75 being loose on the said stud shaft 74 and the gear 75 being in mesh with a smaller gear or pinion 76 which is fixed to gear 12 by hub 77 and which imparts motion to the gear 75 from gear 12, which is secured to shaft 11, and consequently, when gear 12 is ro-

tated motion is simultaneously imparted to the shaft 33 through the intermediary of gears 76, 75, 73 and 72, and to the sprocket wheels 34, 35, through the intermediary of pinion 68, shaft 67, pinions 65, 66 and gears 63, 64, but at a continuous or uniform rate of speed, while the motion of the shaft 33 and grippers 45 mounted thereon is differential, the speed being highest when the elliptical gears 72, 73 are in the position shown in Fig. 4, where the grippers 45 have obtained possession of the sheet, and slowest where the elliptical gears have made a half rotation, toward which point the speed of the grippers 45 gradually diminishes until they arrive at their minimum speed, where they open to allow the sheet to drop upon the table 32. From this point the speed of the grippers 45 gradually increases until they arrive at the point where they are to receive the sheet, where they are open and the sheet is forced into their grasp by the tapes 14 and roller, or rollers, 16, each of the grippers 45 being provided at its extremity with a stop 78 in the form of a small angle-iron secured to the under side thereof for preventing the sheet from being pushed under the gripper beyond a certain extent. When the grippers 45 catch the sheet it is otherwise released from the pressure of the roller 16, as before intimated, and at the same time the guide fingers 18 are raised out of contact therewith. This movement of the roller 16 and fingers 18 may be accomplished by a cam 79 secured to shaft 11 and serving to deflect an arm 80 which carries at one end an anti-friction roller 81 bearing against cam 79, while its other end is secured to a rocker shaft 82 which carries arms 83 supporting a rod 84, upon which the fingers 18 are secured, and these arms 83 also carry the roller 16, so that when the dwell of cam 79 arrives under the roller 81, the roller 16 will descend upon the tapes 14 and cause the tapes to pinch and advance the sheet, but when the major diameter of the cam 79 reaches and deflects the roller 81 the sheet is released by the roller 16, and the fingers 18 simultaneously elevated so as to allow the smoothing roller 44 to draw the sheet forward.

The sheet inverting roller 44 may be supported and journaled upon the chains 40, 41, in any suitable way, such, for example, as by extending its journals 85 into the hollow pins 86 which hold the links of the chain together, these pins being preferably constituted or formed on one side of the link and passing through the block and other side of the link, as shown in Fig. 3, but any other suitable construction may be employed.

Vertical screws 91 operatively connected to the cross shaft 92 are shown for adjusting the elevation of the table 32, as usual with sheet delivery mechanisms.

4

By the means described it will be seen that if the sheet be delivered or fed by the feeding devices 14, 16, or by any other means, with the last printed or treated side up, to 5 the delivery mechanism, it will be delivered upon the table 32 with such last printed or treated side down, the roller or bar 44 thereby avoiding the side last printed or treated during the delivery operation while at the 10 same time serving as a positively acting means for engaging and inverting the sheet during the time the forward end of the sheet is held by the grippers 45. By being thus engaged by the roller at one point and held 15 by the grippers 45 at the end, the entire sheet, less the small portion which laps over the roller 44, is held in substantially a horizontal position while the roller 44 is completing its outward travel, and while the 20 sheet rests at one end upon the fingers 19, these, together with the roller 44 serve to hold it in substantially a horizontal position.

Having thus described my invention, what I claim as new therein and desire to secure 25 by Letters Patent is:

1. A sheet delivery mechanism, comprising in combination means for engaging and holding the advance edge of the sheet, means for positively supporting the sheet in 30 substantially a horizontal position and means movable back and forth in a non-circular path of travel for engaging and inverting the sheet while thus held and supported.

35 2. A sheet delivery mechanism, comprising in combination means for printing or treating the sheet, means for conducting the sheet away from said printing or treating means, treated side up, means for holding 40 the advance edge of the sheet and means movable past said holding means and in the direction of movement of the sheet for engaging the untreated side of the sheet and inverting it.

45 3. A sheet delivery mechanism, comprising in combination means for printing or treating the sheet, means for conducting the sheet away from said printing or treating means, treated side up, means movable at as 50 great a rate of speed as the sheet for engaging and holding the advance edge thereof, and means movable past said holding means for engaging and inverting the sheet while thus held.

55 4. A sheet delivery mechanism, comprising in combination means for holding the advance edge of the sheet and means for engaging the sheet while thus held and deflecting it past said holding means, said deflecting 60 means being movable around said holding means.

65 5. A sheet delivery mechanism, comprising in combination movable means for holding the advance edge of the sheet, means for engaging the sheet while thus held and de-

flecting it past said holding means, said deflecting means being movable continuously around the line of movement of said holding means.

6. A sheet delivery mechanism, comprising in combination means for advancing the sheet from the machine in which it was treated, means movable in the direction of movement of said advancing means, for engaging and holding the advance edge of the sheet, and means movable entirely around said holding means and in the same direction for engaging and inverting the sheet while thus held.

7. A sheet delivery mechanism, comprising in combination means for holding one edge of the sheet, a receiving table or surface, and means movable in a substantially straight course over said holding means and across said table for engaging and inverting the sheet.

8. A sheet delivery mechanism, comprising in combination means for holding one edge of the sheet, a sheet-smoothing means and traveling flexible carrying means for moving said sheet smoothing means against and deflecting, and thereby inverting the sheet.

9. A sheet delivery mechanism, comprising in combination means for holding one edge of the sheet, a sheet smoothing means, and a continuous flexible carrying means for moving said sheet smoothing means against and inverting the sheet.

10. A sheet delivery mechanism, comprising in combination means for holding one edge of the sheet, a sheet smoothing means, a flexible carrying means encompassing said holding means for moving said sheet smoothing means against and inverting the sheet.

11. A sheet delivery mechanism, comprising in combination means for holding one edge of the sheet, means for moving said means at a differential rate of speed, and means for engaging and deflecting the sheet while thus held, for inverting it.

12. A sheet delivery mechanism, comprising in combination means for holding one edge of the sheet, means for causing said holding means to engage and then release the sheet, means for moving said holding means at a differential rate of speed, decreasing toward the position where the sheet is released, and means for engaging and deflecting the sheet while thus held.

13. A sheet delivery mechanism, comprising in combination means for holding one edge of the sheet, means for engaging and deflecting, and thereby inverting the sheet, while thus held, and a continuously moving belt carrying said deflecting means.

14. A sheet delivery mechanism, comprising in combination means for holding one edge of the sheet, means for engaging and

deflecting, and thereby inverting, the sheet while thus held, and two continuously moving belts carrying said deflecting means and being unobstructed between their outer ends 5 to permit the sheet to fall between them.

15. A sheet delivery mechanism, comprising in combination means for feeding the sheet away from the machine in which it was printed or treated, means moving at substantially the same rate of speed as said feeding means and in the same direction for engaging and holding one edge of the sheet, and a positive means movable in a non-circular path of delivery past said holding means for 10 engaging the sheet and deflecting it in a direction away from said feeding means.

16. A sheet delivery mechanism, comprising in combination two belts, a revolving means for engaging and holding one edge of the sheet, differential speed mechanism for revolving the last said means, means for driving said belts a greater travel than the distance traveled by said holding means, and means carried by said belts for engaging and 20 inverting the sheet while held by said holding means.

17. A sheet delivery mechanism, comprising in combination a movable gripper for receiving and engaging the sheet, a stop carried by said gripper for limiting the movement of the sheet with relation to the gripper, and means movable past the gripper for engaging and inverting the sheet.

18. A sheet delivery mechanism comprising in combination the means for printing or treating the sheet, means for conducting the

sheet away from said printing or treating means treated side up, sheet smoothing means for engaging against the other side of the sheet and inverting the same, and means 40 for engaging and holding the advance edge of the sheet while being thus inverted, the space above the line of movement of said inverting means being unobstructed whereby the upper side of the sheet will be free from 45 contact while acted on by said smoothing means.

19. A sheet delivery mechanism, comprising in combination means for engaging during the delivery operation and holding the 50 advance end of the sheet, means for supporting the entire sheet in substantially a horizontal position, and means movable in a continuous non-circular line of travel for engaging and inverting the sheet while thus 55 held and supported.

20. In a sheet delivery mechanism, the combination of means for carrying a sheet forward, independent means for seizing the leading edge of the sheet, and means for 60 moving the seizing means out of the way of the means for advancing the sheet whereby the front of the sheet will be formed into a loop with one end held by the seizing means 65 so that the forward movement of the means for advancing the sheet will turn the sheet over.
